COUPLING APPARATUS FOR FLOATING
DRY DOCKS

Frederic R. Harris, New York, N. Y.

Original application December 20, 1943, Serial No. 514,952, now Patent No. 2,370,957, dated March 6, 1945. Divided and this application September 28, 1944, Serial No. 556,237

13 Claims. (Cl. 114—46)

1

This invention relates to improvements in floating dry docks adapted to be built in separate and distinct units, which can be connected to make the dock complete and ready for use.

An object of the invention is to provide a simple, efficient and durable coupling by which the different units of the dock can be operatively attached to one another, and conveniently disconnected whenever necessary to repair, scrape or paint any part of the dry dock, or move it to another site.

Another object is to provide a coupling which will secure the units together, but allow a predetermined degree of up and down movement of the several units under special conditions.

With these and other objects and advantages, which will appear as the description proceeds, the invention resides in the features of construction defined and pointed out; but the embodiment illustrated and set forth is presented as an example only; and others may be adopted in practice to the full extent consistent with the broad and general meanings of the terms in which the appended claims are expressed.

On said drawings:

Figure 1 is a side elevation on a small scale of an assembled dock having its constituent units connected by couplings according to this invention.

Figure 2 shows in end elevation part of the hull and one side wall of one unit of the dock with one coupling member on the end of the wing wall, for connecting one unit to another.

Figures 3 and 4 are respectively a side and a top elevation of such a coupling member in operative position.

Figures 5 and 6 are front elevations of complementary engaging parts or members of the coupling device for the units of the dock; one part to be mounted on one unit and the other on an adjacent unit.

Figure 7 is a section on line 7—7 of Figure 5.

Figure 8 is a front view of the structure appearing in Figure 7, showing one side only.

Figures 9 and 10 are horizontal sections on lines 9—9 and 10—10 of Figures 5 and 6 respectively.

Figure 11 shows in horizontal section the coupling members of Figures 5, 6, 9 and 10 in connecting position.

Figure 12 is a vertical section on line 12—12 of Figure 11, through the coupling, showing one member only; and

Figures 13 and 14 are respectively a front view partly in section and a top view of the coupling head.

2

The same numerals identify the same parts throughout.

This application is a division of my prior application for patent on a Prefabricated timber dock, Serial No. 514,952, filed December 20, 1943, now Patent No. 2,370,957, dated March 6, 1945.

Each dry dock unit comprises a pontoon having a hull 1 with portions of side walls 2 at each of its shorter sides or ends. By joining several such units with the two walls thereon arranged end to end, in alignment along each side, a complete dock is produced. The couplings indicated at 3 (Figure 1) on the ends of the portions of the side walls of adjoining units connect the various units to one another. The framework of the hull and the parts of the side walls of the dock thereon for each unit, are indicated in Figures 2, 3 and 4, and described fully in my said prior application. The framework of each unit is covered entirely with planking to make it water-tight, and the couplings are supported in position on the outside of the planking.

The couplings 3 for the dock units embrace complementary parts, one of which 3a is mounted on one end of a length of wall upon one hull, and the other 3b upon the opposing end of a length of side wall of an adjacent hull. The member 3a forms the head member of the coupling; the other 3b, the socket member by which 25 the head is held. In operation the head members are permitted to slide up and down in the socket members as the couplings hold the dock units together. Thus, the dock units, in sinking, raising and trimming can be managed and controlled independently of one another. If one unit is pumped out or filled more rapidly than the next, no stress on the couplings ensues because the units are allowed to rise or sink to some extent independently. When this happens the 30 pumps are slowed or accelerated, to bring all units into proper position, that is, to the same level.

In structure the head member comprises vertical I-beams 51, extending from the floor of the dock upward along the end of a length of wall 2. They are affixed by welding their flanges to intervening space plates or shims 52 which are welded to plates 21c projecting out at the extremities of upper and lower chords of trusses 8' in the walls 2; the ends of beams 51 being 45 between the plates 21c. At their lower ends these beams are joined by a horizontal beam 53 welded in place; through similar intervening plates or shims; which are shown in Figures 5 and 6 but are omitted from Figures 9, 10 and 11 50 for the sake of clearness; and higher up but at 55

a distance below the upper ends of the beams 51 is a cross-beam 54. This cross-beam is fitted to the beams 51 and attached thereto at its ends by bolts and angle irons indicated at 55, engaging the webs of the two beams; and can easily be put into place and removed. The web of the beam 54 can be extended beyond the flanges by cutting away the latter, for this purpose. The two horizontal beams 53 and 54 are connected by vertical beams 56 in the space between the beams 51, also removably attached at upper and lower ends by bolts and angle members 55. To the beams 56 the head 57 is affixed. It projects outward beyond the faces of the beams 56; and is retained by the socket member 3b, when the couplings connect the dock units together.

The socket member also comprises vertical beams 51' mounted in the same position on plates 21c' at the end of the wall of the next unit, at the same side, and secured as before to trusses 8' and connected as before, and at the same points, by horizontal beams 53' and 54', the latter again being removably attached by bolts and angles 55'; and the former permanently secured in place. In the space between these beams 51', the beams 53' and 54' are joined by flat beams 58, each consisting of a front flange 58a and back flange 58b, united by two webs 59. The webs 59 are cut or rabbeted at their lower ends to fit upon the top flanges of the beams 53' and are welded thereto; at their tops the beams 58 are detachably joined to beam 54' by bolts and angle irons 55' attached to the webs 59. Near their tops the beams 58 are braced by short lengths of I-beams 65 welded to the outer webs 59 at one end and at the other to T-plates 66 welded in turn to the beams 51'. The inside webs 58b are spanned by a plate 64 welded on behind them at the level of the members 65. The beams 58 are further joined by two cross-beams 61, just below the plate 64 and above the beam 53, with plates 62 welded on their ends to be bolted at 63 to the inner webs 59 (Figures 7 and 8), so that these beams 61 can be readily dismounted. Between the horizontal beams 61 the flanges 58a and 58b are wider, extending over the inside webs 59, so as to overlap and engage the projecting ends of the head 57. The webs 59 taper to shorter width at top and bottom and the flanges 58a have sloping portions 60. The beams 58 and inner webs 59 form vertical guideways for the head 57.

The head 57 may be hollow and made up of metal plates forming front and rear faces 66, top and bottom faces 67, and ends 68. Inside are vertical reinforcing webs 69 parallel to the ends and inside horizontal reinforcing bars or webs 70 connecting the webs and ends. Upon the front and rear faces adjacent the ends are convex reinforcing bars 71. Bars or webs 72 welded to the head and beams 56 hold the head in position. These webs 72 are not so far apart as the ends of the head, which are thus in effect transversely extended.

To connect the units of the dock, as appears in Figure 1, the beams 54' of the socket members 3b are unbolted and dismounted; so are the upper beams 61. One unit is then partly flooded and lowered sufficiently in the water. The next section is brought near enough to locate the heads 57 between the beams 51' of the sockets, in-line with the spaces above the beams 53'. The one unit can now be pumped out and raised or the other lowered until the heads 57 drop between the beams 58, with the ends 68 between the front

beams 58a at their widest parts. Beams 54' and 61 are then bolted into place again. The units are then coupled but the heads 3a can slide up and down in the members 3b, and the upper beams or elements 61 prevent disengagement.

The units can also be connected simply by moving them close together with the beams 54 and 61 of the members 3b, and the heads 57, beams 56 and associated cross-beams 54 removed. The heads 57 can be engaged with the socket guideways, and the said beams then securely attached in proper positions.

When the dock is assembled and the couplings engaged to hold the various units together, each unit comprising a hull with portions of side walls 2, all of which are in alignment when the dock is assembled, the various units can then, if desired, be rigidly connected together by cross-beams or other devices extending from one unit to the other.

Having described my invention, what I believe to be new is:

1. A floating dry dock hull having walls thereon, a pair of external upright beams at the end of one of said walls, horizontal beams uniting the upright beams, a pair of vertical beams between the latter uniting said horizontal beams and a head with a transversely extended outer end secured to the last named upright beams.

2. A floating dry dock hull having walls thereon, a pair of external upright beams at the end of one of said walls, horizontal beams uniting said upright beams, and means forming vertical guideways between said last named beams and secured to said horizontal beams.

3. A floating dry dock comprising two or more units and coupling means for connecting said units, said means comprising a member having a head with transversely extended ends on one unit and a member having opposed flanges on an adjacent unit disposed to overlap said ends and retain said head between them but allow up and down motion of the head.

4. The floating dry dock according to claim 3 wherein the second named member also has an element for preventing disengagement of said head.

5. A floating dry dock comprising two or more units, each having portions of side walls thereon, and coupling means on the ends of said walls to connect said units, each of said means comprising a member having a head with transversely extended ends on one unit, and a member having a vertical guideway on an adjacent unit disposed to overlap said ends and retain said head.

6. The floating dry dock according to claim 5 wherein the second named member also has an element spanning the top of the guideway to prevent disengagement of said head.

7. A floating dry dock hull having walls thereon, said walls containing girders comprising upper and lower horizontal beams, a pair of external upright beams affixed to said horizontal beams at the end of one of said walls, cross-beams uniting the upright beams, a pair of vertical beams between the latter uniting said cross-beams and a head with transversely extended ends secured to the last named upright beams.

8. A floating dry dock hull having walls thereon, said walls containing girders comprising upper and lower horizontal beams, a pair of external upright beams affixed to said horizontal beams at the end of one of said walls, cross-beams uniting said upright beams, and means

forming vertical guideways between said last named beams and secured to said cross-beams.

9. The floating dry dock according to claim 8 wherein said guideway has a retaining element spanning the top thereof.

10. A floating dry dock comprising multiple units, and coupling means therefor, each of said means comprising a member on one unit having vertical beams attached to said unit, cross-beams uniting the vertical beams, additional vertical beams affixed to said cross-beams and a head having extended ends supported by said additional beams, and a complementary member on an adjacent unit comprising vertical beams, cross-beams uniting same, means forming a vertical guideway mounted on said cross-beams to receive the head and an element spanning the guideway at the top to prevent disengagement of said head.

11. A floating dry dock embracing multiple units having side walls thereon, said walls containing trusses with upper and lower horizontal beams therein, and coupling means for said units, said means comprising vertical beams on the end of a side wall of one unit and secured to the horizontal truss beams of said wall, cross-beams connecting the vertical beams, additional vertical beams supported by the cross-beams, and a projecting head with extended ends mounted on the additional vertical beams, and a complementary member on the opposing end of the wall of an adjacent unit comprising vertical beams affixed to the horizontal truss beams of said last

named wall, cross-beams uniting said vertical beams, a vertical guideway attached to said cross-beams to receive and hold said head and an element spanning the top of said guideway to prevent disengagement of said head.

12. A floating dry dock hull having walls thereon, said walls containing girders comprising upper and lower horizontal beams, a pair of external upright beams affixed to said horizontal beams at the end of one of said walls, cross-beams uniting the upper and lower ends of said upright beams, means for detachably securing the cross-beam at the upper end of said upright beams in place, and means forming vertical guideways between the upright beams and secured to said cross-beams.

13. The floating dry dock according to claim 12, wherein said guideway has retaining elements at the upper and lower ends thereof, the upper retaining element being removably secured in place.
